185,363

COMBINED COLLAPSIBLE TUBE AND DISPENSER FOR LIQUIDS

Ian Holt, Van Nuys, Calif.

Application July 24, 1958, Serial No. 51,919

Term of patent 14 years

(Cl. D58—26)

FIG. 5.

FIG. 6.

FIG. 7.

Fig. 1 is a side elevation of a combined collapsible tube and dispenser for liquids showing my new design.

Fig. 2 is a side elevation of the opposite side of Fig. 1.

Fig. 3 is a top plan view of Fig. 2.

Fig. 4 is a bottom plan view of Fig. 2.

Fig. 5 is an end view of Fig. 1 looking from left to right.

Fig. 6 is an end view of Fig. 1 looking from right to left.

Fig. 7 is a perspective view thereof.

I claim:

The ornamental design for a combined collapsible tube and dispenser for liquids, substantially as shown.
